(57) **CLAIM**

The ornamental design for the trash can, as shown and described.

DESCRIPTION

FIG. 1 is a perspective view of the trash can according to the present invention;

FIG. 2 is a front plan view of FIG. 1;

FIG. 3 is a top plan view of FIG. 1; and,

FIG. 4 is a left side plan view of FIG. 1; the right side being identical.

The body of the trash can is shown broken away to indicate that no specific height is claimed.
